DESIGN FOR A BRACELET OR THE LIKE

Marion O'Brien, New York, N. Y.

Application March 26, 1941, Serial No. 99,909

Term of patent 7 years

To all whom it may concern:

Be it known that I, Marion O'Brien, a citizen of the United States and a resident of the city of New York, Borough of Manhattan, in the county and State of New York, have invented a new, original, and ornamental Design for a Bracelet or the Like, of which the following is a specification, reference being had to the accompanying drawing, forming part thereof, in which—

Fig. 1 is a perspective view of a bracelet showing my new design;

Fig. 2 is a front elevation of the bracelet;

Fig. 3 is a side elevation of the bracelet;

Fig. 4 is a top plan view of the bracelet.

I claim:

The ornamental design for a bracelet or the like, substantially as shown.

MARION O'BRIEN.
